Primary Examiner — John Windmuller*Assistant Examiner* — John R Yeh(57) **CLAIM**

The ornamental design for a remote control unit, as shown.

DESCRIPTION

FIG. 1 is a perspective view showing my design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof; and,
 FIG. 7 is a bottom plan view thereof.

1 Claim, 3 Drawing Sheets(56)
